UNITED STATES PATENT OFFICE.

FREDERICK C. MONIER, OF NEW BRITAIN, CONNECTICUT, ASSIGNOR TO NORTH & JUDD
MANUFACTURING COMPANY, OF NEW BRITAIN, CONNECTICUT, A CORPORATION.

DESIGN FOR A BRIDLE-CHEEK.

42,366.

Specification for Design.

Patented Mar. 26, 1912.

Application filed January 10, 1912. Serial No. 670,505. Term of patent 14 years.

To all whom it may concern:

Be it known that I, FREDERICK C. MONIER, a citizen of the United States, residing at New Britain, in the county of Hartford and State of Connecticut, have invented a new, original, and ornamental Design for Bridle-Cheeks, of which the following is a specification, reference being had to the accompanying drawing, forming part thereof.

The figure is a perspective view of a bridle check showing my new design.

I claim:—

The ornamental design for a bridle cheek, as shown.

FREDERICK C. MONIER.
